*Fig. 3*FIGURE 1 is a front perspective view;
FIGURE 2 is a side view; and

FIGURE 3 is a rear perspective view.

In view of the prior art, the characteristic feature of my design resides in the overall appearance resultant from the specific appearance of the seat or saddle area of the bicycle, particularly the seat or saddle itself and its three supporting elements, in combination with the rest of the bicycle, as shown.

I claim:

The ornamental design of a bicycle, substantially as shown and described.
